UNITED STATES PATENT OFFICE

165,593

SWING

Roy Glenn Low, Minneapolis, Minn.

Application April 17, 1950, Serial No. 9,275

Term of patent 7 years

(Cl. D34—15)

To all whom it may concern:

Be it known that I, Roy Glenn Low, a citizen of the United States of America, residing at Minneapolis, in the county of Hennepin, and State of Minnesota, have invented a new, original, and ornamental Design for a Swing, of which the following is a specification, reference being had to the accompanying drawing, forming part thereof.

In the drawings:

Fig. 1 is a perspective view of a swing, showing my new design;

Fig. 2 is a side elevational view thereof;

Fig. 3 is a front elevational view thereof; and

Fig. 4 is a top plan view thereof.

The supporting members shown in dotted lines are for illustrative purposes only.

I claim:

The ornamental design for a swing, as shown and described.

ROY GLENN LOW.
